CLAIM

The ornamental design for a novelty headwear, as shown and described.

DESCRIPTION

FIG. 1 is a top plan view of novelty headwear showing our new design;

FIG. 2 is a front elevational view thereof;

FIG. 3 is a side elevational view thereof, the opposite side view being a mirror image thereof;

FIG. 4 is a rear elevational view thereof;

FIG. 5 is a bottom plan view thereof; and

FIG. 6 is a smaller perspective view of the novelty headwear.
